UNITED STATES PATENT OFFICE

JOHN H. TRENKLER AND WARREN A. KING, OF HORNELL, NEW YORK

EXTENSION TABLE

Application filed May 7, 1929. Serial No. 361,180.

The present invention relates to extension tables and more particularly to the type in which a movable top section is shiftable from a position under a stationary top section to a position in a plane with the stationary top section or vice versa.

An object of the invention is to provide a construction which will be inexpensive to manufacture, simple in operation, and durable in use. Another object of the invention is to provide a construction which requires no tilting movement of the movable top section to shift it to and from its position of use. A further object of the invention is to provide a novel extension slide of compact construction containing the means for controlling the movement of a movable top section from its inner to its outer position and vice versa. A still further object of the invention is to provide a novel means of causing the simultaneous movement of two top sections upon the movement of one of them to or from collapsed position.

To these and other ends, the invention consists of certain parts and combinations of parts all of which will be hereinafter described: the novel features being pointed out in the appended claims.

In the drawings:

Fig. 1 is a side view of a table with parts broken away;

Fig. 2 is a fragmentary sectional view showing the extension slides in end elevation and the parts carried thereby;

Fig. 3 is a side view of the center members of the extension slide;

Fig. 4 is an inverted view of the inner face of one of the movable members of an extension slide;

Fig. 5 is a bottom view of an extension slide showing the means connecting the movable members of an extension slide for simultaneous operation;

Fig. 6 is a fragmentary enlarged view of the center member of an extension slide showing the manner in which the switch operates between the two guides; and

Fig. 7 is a section on the line 7—7 Fig. 5.

In the illustrated embodiment of the invention, 1 indicates a base from which rises

two pedestals 2 connected at their upper ends by a cross piece 3. In this instance, this cross piece supports two extension slides each comprising a center member 4 and two side members 5.

Each center member 4 is, in this instance, stationary being connected to the cross piece 3 to project from both sides thereof. At its middle portion each center member 4 has an upwardly projecting rest 6^a and a stationary top section 7^a is rigidly secured to the rests 6^a of the center members of the two extension slides.

The two movable members or sections 5 of each extension slide are provided each with a rest 8 near its outer end to which a movable top section 9^a is rigidly secured, there being connected two of such movable sections 5 one on each extension slide.

With the end in view of guiding each movable section 5 on the stationary section 4, one of said sections, in this instance, the stationary section is provided with two sets of ways, the sets being arranged in different horizontal plane and also at different points in the length of the slide. Each set, in this instance, comprises a short way 6 and a long way 7 parallel with and below the way 6. A short junction way 8^a connects the two ways 6 and 7 at one end and extends beyond such ways in a horizontal plane between the two.

On the two sets of ways on opposite sides of the center member or section 4 operate devices 9 in the form of two projections or rollers on the inner face of each movable member 5 in different horizontal planes and at different points in the lengths of the members 5. By having two sets of ways and two projections for each movable member 5, the latter travels from its inner to outer position or vice versa without any tilting movement of the movable slide members 5. The raising and lowering movements of the slides from one parallel way to the other is effected by the converging walls 10 adjacent and leading to the junction portion 8^a.

With the end in view of directing each projection 9 alternately to the two ways 6 and 7 a movable switch 11 is provided at the junction way between the converging walls 10, this

switch 11 being pivoted at 12 and when in one position directing a projection 9 into the upper way 6 and in another position directing a projection into the lower way 7.

5 To effect the shifting of the movable switch member, a switch shifting means is employed comprising, in this instance, a member which is mounted between the two ways to swing and to slide during such swinging. In this 10 instance, this member has a head portion 12^a and a stem portion 13. The stem portion 13 is guided in a guide 14 while the head part 12^a is provided with a straight slot 15 in which lies a fixed pin 16. A spring 17 has an abutment 18 one end against the shifter and its other end against the guide 14. The head portion of the shifter is so arranged that in one extreme position determined by the slot 15 it projects into the way 6 and in the other 20 extreme position it projects into the way 7 in the path of a projection 9 travelling on said ways. When a projection 9 engages the head portion of the shifter it compresses the spring 17 until the center of the slot 15 is 25 passed by the pin when the spring 17 expands and projects the shifter into the other way.

Connection between the shifter and the switch is effected, in this instance, through a 30 projection 18 on the shifter operating between two spaced abutments 19 on the switch. As the switch shifter is moved by a projection 9 it first moves independently of the switch but upon the expansion of the spring 17 the 35 shifter strikes the other abutment on the switch member and kicks the switch into the path of the projection 9 travelling toward the junction way so that the projection must displace the switch before the projection enters 40 the junction way, the spring permitting the yielding of the switch but returning the switch immediately to the position to which it is carried by the shifter.

45 Simultaneous movement of the two top extension members in opposite directions may be effected by providing each center member of each extension slide with a two armed lever 20 pivoted at 21 between its ends to the under side of a center member and having 50 links 22 pivoted at 23 to its opposite ends and at 24 to the outer faces of the slide members.

55 The center members may each be provided with guide straps 25 which extend from opposite sides of the under surface of each center member under the side members and upwardly on the outer faces of the side members holding the latter to the center member.

60 In operation, assuming that the top extensions lie beneath the fixed top, as shown in Fig. 1, and it is desired to extend the table at this time the projections 9 lie in the ways 7 and the switch shifters project into such ways. One of the top extensions is pulled 65 outwardly and the projections 9 travel in the ways 7 until the switch shifters are engaged,

shifting the switches into the path of the projections 9 before the junction ways are reached. As the projections 9 engage the switches, the latter yield and spring back into the paths of the projections. When the 70 projections reach the junction ways the top extensions are lying beyond the outer sides of the top so that the extensions are required to be moved toward the top and in doing this the projections 9 are directed by the switches into the upper ways 6 on which they travel until the top extensions abut at their inner edges the outer edges of the fixed top as shown in dotted lines in Fig. 1. To move the top extensions to their inner positions, the top extensions are again pulled outwardly until the 75 switches are shifted and are then moved inwardly to positions beneath the fixed top.

What we claim as our invention and desire to secure by Letters Patent is:

1. The combination with a table top and a top extension, of an extension slide including two members one rigid with the top and the other rigid with the top extension, one of said slide members having two sets of ways at different points in the length of the member and also in different horizontal planes, each of said sets comprising two parallel ways and a junction way between them, and the other of said slide members having two projections at different points in the length of the member and also in different horizontal planes, each of said projections operating on one of said ways and serving to hold the top extension against tilting in the movement of said top extension from an inner position under the top to an outer position in the plane of the top or vice versa.

2. The combination with a table top and a top extension, of an extension slide including two members, one of which is provided with two parallel ways connected at one end, a projection carried by the other slide member and operating in said ways, a movable switch at the junction of the ways, and a movable switch shifting means for shifting the switch so that the projection is directed to travel alternately on the two ways when carried to the junction point, said means having portions alternately projected into the two ways by the projection.

3. The combination with a table top and a top extension, of an extension slide including two members, one of which is provided with two parallel ways connected at one end, a projection carried by the other slide member and operating in said ways, and means alternately projected into the path of the projection so as to direct the projection alternately into the two ways on successive movements of the projection to the junction between the ways.

4. The combination with a table top and a top extension, of an extension slide including two members, one of which is provided with

two parallel ways connected at one end, a projection carried by the other slide member and operating in said ways, a movable switch at the junction of the ways, and a movable switch shifter mounted to be projected into the path of the projection as it travels along either way and connected to the movable switch to shift the latter as the projection approaches the junction on one way to direct 10 the projection into the other way from said junction point.

5. The combination with a table top and a top extension, of an extension slide including two members, one of which is provided with 15 two parallel ways connected at one end, a projection carried by the other slide member and operating in said ways, a pivoted switch at the junction point of the ways having two spaced abutments, a slidable swinging switch 20 shifter arranged to operate between the two abutments on the switch and to be projected into the path of the projection travelling on either way, and a spring acting on the switch shifter to hold it in either of its positions and 25 to permit the switch to yield in order that the projection may pass the switch after shifting the latter so as to reach the junction way to pass to the other way.

6. The combination with a fixed table top 30 and two top extensions, of an extension slide including three members, one rigid with the top and the other two movably arranged on opposite sides of and movable on the first mentioned member but each rigid with one 35 of the top extensions, the member rigid with the top having on opposite sides thereof two ways and a junction way connecting them at one of the ends, a device carried by each of the slide members on the top extensions and 40 operating in one of the ways to support a top extension in a plane with the top and in the other way to support a top extension under the top, and equalizing means connecting said movable members for movement in opposite 45 directions.

7. The combination with a table top and a top extension, of an extension slide including two members, one of which is provided with two parallel ways connected at one end, a projection carried by the other slide member and operating in said ways, a movable switch at the junction of the ways, and a shifter having connection with the switch for effecting the movement of the switch alternately in opposite 50 directions to direct said projection to travel alternately on the two ways when it reaches the junction between them.

8. In a table, the combination with a stationary top and a top extension, of an extension slide embodying two members, one of which is rigidly secured to the top and the other of which is rigidly secured to the top extension, and means between the two slide members for guiding them in two horizontal 60 planes one above the other, said guiding 65

means embodying a projection on one of the members, two ways on the other member in which the projection operates, said ways communicating at one end, a switch arranged at the point of communication between the ways, 70 and means for shifting the switch first in one direction and then in the other on each movement of the top extension to its outer position to cause the top extension to travel inwardly alternately in different horizontal planes. 75
